POCKET COMB

John N. Jamo, Grand Rapids, Mich.

Application January 31, 1949, Serial No. 73,710

1 Claim. (Cl. 132—15)

1
The present invention relates to pocket combs. The primary objects of the invention are to provide a pocket comb and a sheath therefor which may be secured within the wearer's pocket in much the same manner as a fountain pen or pencil having a pocket clip; to provide means whereby the comb is securely maintained within the sheath when so positioned in the wearer's pocket, said means being yieldable to permit manual withdrawal of the comb from the sheath for use; to provide means for preventing complete withdrawal of the comb from the sheath so that the two are inseparable, such means being so devised as to permit easy and instant assembly of the comb within the sheath at the time of manufacture; and in general to provide such a pocket comb which is simple in construction, economical in manufacture and attractive in appearance.

An illustrative embodiment of the invention is shown in the accompanying drawing, wherein:

Figure 1 is a front elevational view of the comb and sheath assembled, the comb being telescoped within the sheath and ready for positioning in the wearer's pocket;

Figure 2 is a vertical sectional view of the same taken on line 2—2 of Figure 1;

Figure 3 is an enlarged horizontal sectional view of the same taken on line 3—3 of Figure 1;

Figure 4 is an enlarged horizontal sectional view of the same taken on line 4—4 of Figure 1;

Figure 5 is an enlarged, fragmentary vertical sectional view of the same taken on line 5—5 of Figure 1; and

Figure 6 is a front elevational view of the comb and sheath with the comb in extended position for use in combing the hair.

Referring now in detail to this drawing wherein like parts are designated by the same numerals in the several views, the device there shown generally comprises a comb element 10 of oblong cross-section and having more or less conventional teeth 11, and a sheath 12 therefor.

The body portion of the sheath 12 comprises as shown an elongated, cross-sectionally oblong, flat base plate 13 and an elongated cover plate 14 of U-shaped cross-section and having its edges secured to the edges of the base plate 13 as by means of a suitable adhesive. If desired, the base plate 13 and cover plate 14 may be of unitary formation. One end of the sheath 12—the lower end as viewed in Figure 1—is open to slidably receive the comb 10 while the other end is provided with a closure here shown as a semicircular continuation of the marginal edges of the cross-sectionally U-shaped cover plate 14. The base

2
plate 13 is provided with a projecting portion 15 which extends upwardly beyond the closed end of the sheath and which is desirably of somewhat ornamental configuration as shown. A pocket clip 16 is mounted on the projecting portion 15 of the base plate 13 as by means of rivets 17, and the lower end of said clip bears toward the cover plate 14 of the sheath so that the sheath may be inserted within the wearer's pocket with the hem of the pocket engaged between the clip 16 and the cover plate 14.

The comb 10 and sheath 12 are preferably formed of a slightly resilient or compressible plastic. At the lower end of the comb as viewed in Figure 1, there is provided a small lug 18 which in the inwardly slid position of the comb engages in a small depression 19 in the inner wall of the sheath to maintain the comb within the sheath. The materials of the comb and the sheath being somewhat resilient, however, and the lug 18 and depression 19 being of somewhat rounded contour, it will be seen that the lug's engagement in the depression is readily yieldable to permit manual withdrawal of the comb from the sheath. A fingernail kerf 20 is desirably provided in the comb's lower or outer end for facilitating this withdrawal of the comb from the sheath.

The comb is provided near its upper or inner end with a pair of oppositely and laterally outwardly extending detents 21, the inner surfaces 22 of which converge inwardly and the outer surfaces 23 of which are substantially perpendicular to the longitudinal axis of the comb. The sheath 12 is provided near its lower or outer end with a complementary pair of oppositely and laterally inwardly extending detents 24, the outer surfaces 25 of which converge inwardly and the inner surfaces 26 of which are substantially perpendicular to the longitudinal axis of the sheath. When the comb is assembled to the sheath at the time of manufacture, said comb is inserted into the open end of the sheath and the contact of the mutually convergent surfaces 22 and 25 of the pairs of detents 21 and 24 on the comb and sheath respectively effects a slight compression of the resilient material of these parts so as to permit the detents 21 on the comb to slide past the detents 24 on the sheath. However, once the comb is assembled within the sheath, complete withdrawal of the comb from the sheath is prevented by contact of the surfaces 23 on the comb's detents 21 with the surfaces 26 on the sheath's detents 24. The comb is thus permanently assembled within the sheath but may be readily manually withdrawn to its position shown

in Figure 6 for its intended use in combing the hair, during which the sheath 12 serves as a handle for the comb.

It will thus be seen that a novelty pocket comb has been provided which may be conveniently carried in the wearer's pocket in much the same manner as a fountain pen or pencil, which is readily accessible for use, and which is so constructed that the comb and its sheath are inseparably assembled. While but one specific embodiment of the invention has been herein shown and described, it will be understood that numerous details may be altered or omitted without departing from the spirit of the invention as the same is defined by the following claim.

I claim:

A pocket comb comprising the combination of an elongated comb element of generally oblong cross-section and a sheath generally conforming to the shape of the comb and adapted to house the comb and having one end thereof closed and the other end thereof open to slidably receive said comb therein; a pair of oppositely and laterally outwardly projecting detents on the inner end of the comb; and a pair of oppositely and laterally inwardly projecting detents in the sheath near the open end thereof; said pairs of detents

having cooperable surfaces converging toward the closed end of the sheath and adapted to permit insertion of the comb within the sheath and one of said pairs of detents being slightly resilient to permit such insertion, and said pairs of detents having other surfaces, which, after the comb is inserted within the sheath, are adapted to positively abut to prevent complete withdrawal of the comb from the sheath.
